(57) **CLAIM**

The ornamental design for an LED light, as shown and described.

DESCRIPTION

FIG. 1 is a front, top, left perspective view of the LED light; FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The claimed design is indicated by the relatively dark portions in the drawings, while the relatively light portions are form no part of the claimed design. Shading is used to illustrate the curvature of the LED light.

1 Claim, 7 Drawing Sheets
